UNITED STATES PATENT OFFICE.

EDWARD G. SHORTT, OF CARTHAGE, NEW YORK.

CARBURETER.

1,179,568.

Specification of Letters Patent.

Patented Apr. 18, 1916.

Application filed November 28, 1911. Serial No. 662,908.

To all whom it may concern:

Be it known that I, EDWARD G. SHORTT, a citizen of the United States, residing at Carthage, in the county of Jefferson and State of New York, have invented certain new and useful Improvements in Carbureters; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in apparatus for automatically controlling the mixing of air and fuel to be applied to engines, etc., the object in view being to absolutely regulate the supply of fuel at any speed at which the engine runs, thereby resulting in an appreciable saving of fuel and a gain in power.

In the usual operation of carbureters, it is customary to regulate same for a certain speed and power, and any variation from its adjustment is at the expense of fuel and power, whereas by my improved controlling device, the quantity of air and fuel being fed are at all times proportionate to each other irrespective of varying speeds.

The invention comprises various other details of construction and combination of parts as will be hereinafter more fully described and then specifically defined in the appended claims.

My invention is illustrated in the accompanying drawings, which, with the letters of reference marked thereon, form a part of this application and in which:—

Figure 1 is a vertical sectional view through my improved air and fuel controlling apparatus. Fig. 2 is a sectional view on line 2—2 of Fig. 1. Fig. 3 is a side elevation of the apparatus. Fig. 4 is a bottom plan view, and Fig. 5 is an enlarged detail view.

Reference now being had to the details of the drawings by letter, A designates the casing of the controlling device, having a vacuum chamber B, in which a diaphragm C is mounted, held to the marginal edge of the opening in the casing by means of a flanged cap C', through which screws D pass and which engage threaded holes formed in the casing. A second cap, design-

nated by letter E, is also fitted to the opposite end of the casing and has an air inlet opening F' through which the supply of air, to be fed to mix with the fuel, is drawn. A valve F is mounted in said opening and regulates the quantity of air which passes into the air chamber G. Separating said chamber G from the vacuum chamber B is a partition G', having a central tubular opening G², forming a guide for the stem f, of the valve F, and which stem passes through the diaphragm, the latter being held to said stem by means of the collar H, fitted to a contracted portion of the stem and bearing 70 against a shoulder h, at one end, and its flanged end clamping the diaphragm. A suitable washer h' is placed upon the contracted portion of the stem and bears against the under face of the diaphragm, the washer being held in place by means of a nut H'. A coiled spring H² bears between the flange H³ of the collar h and said partition G' and serves to normally hold the diaphragm in the position shown in Fig. 2 when the engine is at rest. Said casing is provided with a second air chamber I, which communicates with the chamber G, through the opening I', and within the chamber I is a spider I², through the center of which is an opening for the stem J of the valve J'. Said stem J has its lower end contracted as at J² where it passes through a flanged collar J³, the upper end of the latter bearing against a shoulder J⁴, and a coiled spring J⁵ about 90 the collar J³ bears between the flange of the collar and said spider and tends to normally hold the valve J' seated. A plug K having a threaded circumference is fitted in the opening at the lower end of the chamber I, and has a diaphragm K² fastened thereto, forming intermediate the same and the plug to which it is attached an auxiliary vacuum chamber K' which communicates with the vacuum chamber B through a duct 100 B'. A screw K³ passes through said diaphragm and has washers K⁴ and K⁵ thereon, the former of which is positioned within the auxiliary vacuum chamber and is provided with a threaded aperture for the reception 105 of the threaded end of the screw, while the washer K⁵ rests against the under side of the diaphragm K² and through which washer K⁵ the screw passes, the latter being accessible through an opening L in the plate L'. The 110 lower end of the stem J rests against the washer K⁴, and is adapted to be given a

slight longitudinal movement when a vacuum is formed in said auxiliary chamber for a purpose which will be hereinafter fully described.

- 5 The seat for the valve J' is beveled and is designated by letter N and through said seat a fuel duct N' leads which is normally closed when the valve J' is seated. The duct N' leads into a chambered portion of the 10 casing, in which a threaded plug N^2 is fitted, and said plug is chambered and has its inner wall threaded for the reception of the screw M which latter is hollow and is interiorly threaded for the reception of the 15 threaded stem of the needle valve M' , the pointed end of which, when the valve is closed, engages a tapering part of said oil duct. The micrometer screw and the screw controlling the needle valve, each is provided 20 with a milled head, affording means for their adjustment. The threads upon the screw may be right or left, accordingly as it may be desired to cause the needle valve to be operated away from or toward its seat 25 to allow a greater or less quantity of fuel to be fed to the carbureting chamber O , as the valve F is opened. In the drawings I have shown left threads upon the outer circumference of the screw. A curved member P 30 has a bifurcated end forming two resilient arms P' , recessed out upon their adjacent faces and designed to receive the unthreaded circumference of the screw, and be held in a clamping relation therewith by means of 35 the screw P^3 passing through registering apertures in said arms, one of the apertures in said arms being threaded whereby, as the screw P^3 is rotated in one direction, the arms may be drawn frictionally against the 40 screw. At one end of the member P is formed a slot Q with flexible walls, the adjacent faces of the walls of the slot being concaved, forming bearing sockets to receive the spherical end R of the connecting link 45 R' . A screw S passes through registering apertures formed in the walls of said slot and engages threads formed in one of the apertures, so that, when the screw S is turned in one direction, the walls of the 50 slot may be drawn toward each other to cause the spherical end of the connecting link R' to be held within its bearing. A similar spherical shaped head R^2 is formed at the other end of the link R' and is 55 swivelly mounted in a socket formed in the end of the valve F . By this connection between the angled member and said valve F , said member is rocked with the movement of the valve and the latter is caused to move 60 truly.

Upon reference to Fig. 2 of the drawings, it will be noted that a coiled spring R^4 is seated in the socket or recess R^3 formed in the end of the valve and against which 65 spring the spherical shaped head R^2 bears.

Said spring R^4 is provided for the purpose of avoiding any unnecessary pressure intermediate the tapering end of the needle valve and its seat in the event of the apparatus being used, for instance, upon engines of limited power and in which the needle valve when, at its farthest outer throw, would only be positioned a very slight distance from its seat and, in the event of the valve F moving slightly under vacuum force 75 formed in the cylinder of an engine to which the apparatus is attached, there would be an unnecessary pressure upon the needle valve after it had been seated and to avoid this the said spring R^4 will allow the valve F to move outward slightly and independent of the needle valve and allow more air to pass through the opening controlled by the valve F .

In order to prevent the formation of a 85 vacuum intermediate the diaphragm C and the plate C' , the wall of the latter is apertured as at C^2 , the wall of the latter being slightly concaved at its inner end forming a seat for the ball valve W , a suitable pin W' , fastened to the plate C' , serving to hold the ball in place. The wall of the aperture C^2 , it will be noted, is provided with a groove or channel V , shown in the detail view Fig. 5 of the drawings, and which affords means whereby any air which might be trapped within the space between the plate C' and the diaphragm C may escape and allow the latter to return gradually to its normal position shown in Fig. 2 of the 100 drawings.

Mounted within the carbureting chamber is a butterfly or other suitable valve X , which may be operated to regulate the vacuum force which acts upon the apparatus. 105

In practice it has been demonstrated that, when the liquid from the duct is directed against the valve J , the beveled edge of the latter will be coated and the groove j therein will become partially filled with moist fuel, and will afford means whereby an eddy will be formed by the air which rushes into the carbureting chamber and catching up any particles of fuel which might lodge in said groove will cause the fuel to be thoroughly mixed before entering the carbureting chamber. Intermediate the carbureting chamber and the vacuum chamber is a duct C^5 regulated by a ball valve C^6 and which latter, upon the initial suction, produced within the cylinder of the engine to which the device is connected, will cause the valve C^6 to unseat as a vacuum is formed in the cylinder of the engine. 115 120 125

When an engine equipped with my improved controlling apparatus is running under high speed, it is desirable to reduce the quantity of fuel being fed in order to secure the proper ratio of fuel to air to ob- 130

tain perfect combustion, the failure to do so being commonly met with in ordinary types of carbureters but which I am able to overcome by my improved automatic fuel-regulating means.

The operation of the invention is as follows:—When the apparatus is at rest, the parts assume the position shown in Fig. 1 of the drawings. The suction produced by the operating piston in the engine to which the device is attached will cause the ball valve C^e to unseat and withdraw the air from the space between the partitions G' and the diaphragm C , thus forming a vacuum therein. As the vacuum chamber B is in unobstructed communication with the auxiliary vacuum chamber K' , the air within the latter will be withdrawn and, owing to the unequal pressures upon the opposite faces of said diaphragms K^2 and C , a longitudinal impulse will be imparted to each of the pistons J and f , unseating each of the valves J' and F , the former of which will uncover the exit end of the fuel port N' , while the latter will allow air to enter the chamber G , being drawn therein by the suction incident to the operation of the working piston. As the valve F unseats, the curved member P , which is connected through the medium of the universal coupling, will rock causing a partial rotary movement to be imparted to the screw M , which in the present instance is shown as being provided with left threads upon its circumference, it being understood that, when the parts are at rest, the needle valve is slightly withdrawn from its seat and, when the air inlet valve is unseated to allow air to be drawn into the casing and by the exit valve into the carbureting chamber, the needle valve will move toward its seat slightly, rather than in the opposite direction which would be the case if the threads upon the screw were right instead of left threads. By this arrangement, an increase of vacuum force produced in the cylinder, with which the carbureting chamber communicates, will cause the fuel to be more rapidly drawn through the fuel exit duct N' into the carbureting chamber, whereas, if the needle moved from its seat upon the increased suction force, a greater supply of fuel would be drawn through said duct.

In the operation of the apparatus, the utilization of the auxiliary vacuum chamber, which causes the diaphragm K^2 to push against the lower end of the piston stem J , tends to counteract the tension of the spring J^e , thus requiring a lesser suction power to unseat the valve J' , while the action of the auxiliary vacuum, formed in the chamber K' , is without effect upon the piston stem at the moment that the full tension of the spring is required to seat the valve. When the engine is idle, the chambers B and K'

will be unsealed, there being sufficient leakage about the valve stems to allow the valves to seat, but when in operation, the leakage will be compensated for and overcome by the suction of the engine, thus producing a sealed chamber and, as a partial vacuum is maintained during the operation of the engine, the diaphragms, which work in unison, will cause the springs to be compressed to balance the vacuum. When the engine is running to produce these conditions and should there be an increase in atmospheric pressure upon the diaphragm, a further compression upon the springs will be effected and consequently will cause both of the air valves J' and F to open farther, thus allowing additional air to enter the combustion chamber. As the fuel supply, open to the atmosphere and subjected to an increase of barometric pressure, will effect the inflow of the fuel correspondingly, in order to avoid an extra supply of fuel being introduced into the engine with the additional supply of air, the needle will have been actuated farther toward its seat to restrict the flow of fuel. By this arrangement the flow of fuel and air will be maintained at the same ratio under varying barometric conditions. For example, should an engine be running at 500 revolutions, a certain stage of vacuum will be maintained which would be constant at any speed and a uniform pressure would be maintained upon the diaphragm but, as the pressure of the atmosphere is not uniform, varying appreciably under barometric conditions, it is obvious that it will be necessary to destroy the tension on the springs in order to allow the diaphragm to be sensitive to the changes in atmospheric pressure.

The essential features in the successful operation of my controller is that the pressures upon the air and fuel are uniformly maintained. The variations of movements of the retarding device are to compensate for the constantly increasing vacuum caused by the increased speed of the engine. In the event of any air being trapped in the space between the diaphragm C and the plate C' , it will be allowed to escape slowly to the atmosphere through the duct or channel formed in the wall of the duct C^2 , thus allowing the diaphragm to return to its normal position, which is that illustrated in Fig. 2 of the drawings.

By the provision of a controlling apparatus embodying the features of my invention means is afforded for regulating absolutely the supply of fuel at any speed at which the piston runs and which will result in an appreciable saving of fuel, the quantity of air and fuel being fed at all times proportionate to each other regardless of variations in speed.

While I have shown my invention in sin-

gle form and having a particular mechanical construction, it will be understood that the apparatus may be varied as to details of construction in various ways without in any way departing from the scope of the invention.

What I claim to be new is:—

1. An apparatus for automatically controlling the feeding of fuel and air to engines, comprising a casing having a carbureting chamber and a vacuum chamber with valve-regulated duct communicating between said chambers, an air chamber, vacuum-actuated valves within the casing, one controlling the air inlet to the air chamber and the other its exit and the oil feed into the carbureting chamber, and means for regulating the quantity of fuel being fed to the carbureting chamber, as set forth. 70
2. An apparatus for automatically controlling the feeding of fuel and air to engines, comprising a casing having a carbureting chamber and a vacuum chamber with valve-regulated duct communicating between said chambers, an air chamber, vacuum-actuated valves within the casing, one controlling the air inlet to the air chamber and the other its exit and the fuel feed into the carbureting chamber, and mechanical means for automatically regulating the quantity of fuel being fed to the carbureting chamber. 75
3. An apparatus for automatically controlling the feeding of fuel and air to engines, comprising a casing having a carbureting chamber and a vacuum chamber with valve-regulated duct communicating between said chambers, an air chamber, valves controlling the air inlet and exit openings in the air chamber, stems fixed to said valves, vacuum-actuated diaphragms adapted to actuate each valve, a fuel controlling valve, and means connecting the latter with the air inlet valve for automatically controlling the quantity of fuel being fed to the carbureting chamber, as set forth. 80
4. An apparatus for automatically controlling the feeding of fuel and air to engines, comprising a casing having a carbureting chamber and a vacuum chamber with valve-regulated duct communicating between said chambers, an air chamber, valves controlling the air inlet and exit openings in the air chamber, stems fixed to said valves, vacuum-actuated diaphragms adapted to actuate each valve, a needle valve controlling a fuel duct leading through the seat of said air exit valve, a screw carrying said needle valve, and connections between the air inlet valve and screw for automatically regulating the supply of fuel, as set forth. 85
5. An apparatus for automatically controlling the feeding of fuel and air to engines, comprising a casing having a carbureting chamber and a vacuum chamber with valve-regulated duct communicating between said chambers, an air chamber, valves controlling the air inlet and exit openings in the air chamber, stems fixed to said valves, vacuum-actuated diaphragms adapted to actuate each valve, a needle valve controlling a fuel duct leading through the seat of said air exit valve, a screw carrying said needle valve, a member fastened to and adapted to rotate the screw and having pivotal connection with the air inlet valve, as set forth. 90
6. An apparatus for automatically controlling the feeding of fuel and air to engines, comprising a casing having a carbureting chamber and a vacuum chamber with valve-regulated duct communicating between said chambers, an air chamber, valves controlling the air inlet and exit openings in the air chamber, stems fixed to said valves, vacuum-actuated diaphragms adapted to actuate each valve, a needle valve controlling a fuel duct leading through the seat of said air exit valve, a screw carrying said needle valve, a member fastened to and adapted to rotate the screw and having swiveled link connections with the air inlet valve, as set forth. 95
7. An apparatus for automatically controlling the feeding of fuel and air to engines, comprising a casing having a carbureting chamber and a vacuum chamber with valve-regulated duct communicating between said chambers, an air chamber, an air inlet valve, a stem connected to said valve, a diaphragm fastened to said stem and forming one wall of the vacuum chamber, an air exit valve and seat therefor through which a fuel duct leads, a stem to said air exit valve, a vacuum-actuated diaphragm adapted to bear against the stem of the air exit valve, a fuel regulating valve, and connections between the latter and the air inlet valve, as set forth. 100
8. An apparatus for automatically controlling the feeding of fuel and air to engines, comprising a casing having a carbureting chamber and a vacuum chamber with valve-regulated duct communicating between said chambers, an air chamber, an air inlet valve, a stem connected to said valve, a diaphragm fastened to said stem and forming one wall of the vacuum chamber, a spring-pressed valve regulating the feeding of air and fuel into the carbureting chamber of the casing, and a vacuum-actuated diaphragm adapted to bear against the end of the stem of the air and fuel regulating valves, as set forth. 105
9. An apparatus for automatically controlling the feeding of fuel and air to engines, comprising a casing having two communicating air chambers therein, one of which is provided with an air inlet opening and the other an exit opening leading into 110

1. A carbureting chamber, a vacuum-actuated valve regulating the air inlet opening, a second valve having a beveled seat through which a fuel duct leads which is controlled by said second valve, a plug fitted in the chambered portion of the casing, a screw having threaded connection with the chambered portion of said plug, a needle valve having threaded connection with the screw and regulating the flow of fuel through said duct, and connections between the micrometer screw and air inlet valve, as set forth.

2. An apparatus for automatically controlling the feeding of fuel and air to engines, comprising a casing having two communicating air chambers therein, one of which is provided with an air inlet opening and the other an exit opening leading into a carbureting chamber, a vacuum-actuated valve regulating the air inlet opening, a second valve, a seat for the latter through which a fuel duct leads, said second valve having a groove in its circumference adapted to receive drip of fuel and cause an eddy to be formed by the air rushing by said groove, thereby thoroughly mixing the fuel before entering the carbureting chamber, a needle valve regulating the fuel duct, and means connecting the needle valve with the air inlet valve, as set forth.

3. An apparatus for automatically controlling the feeding of fuel and air to engines, comprising a casing having two communicating air chambers therein, one of which is provided with an air inlet opening and the other an exit opening leading into a carbureting chamber, a vacuum-actuated valve regulating the air inlet opening, a second and beveled valve, a beveled seat for

the latter through which a duct leads controlled by said second valve, the beveled circumference of the latter having an annular groove therein adapted to catch drip of the fuel and cause the same to be thoroughly mixed by inrushing air by the second valve and which groove forms an eddy, a needle valve regulating the fuel duct, and connections between the needle valve and the inlet air valve, as set forth.

4. An apparatus for automatically controlling the feeding of fuel and air to engines, comprising a casing having a carbureting chamber and a vacuum chamber with valve-regulated duct communicating between said chambers, an air chamber, a spring-pressed air inlet valve, a diaphragm fastened to the stem of said valve, a plate fastened to the casing and having a valved aperture leading through the wall thereof, the marginal edge of the wall of said aperture being grooved to allow air trapped intermediate the diaphragm and said plate to escape to the atmosphere as the diaphragm returns to its normal position, a spring-pressed vacuum-actuated valve controlling the exit of air and the feeding of fuel into the carbureting chamber, a fuel controlling valve, and means intermediate the same and the air inlet valve for automatically regulating the supply of fuel to be fed to the carbureting chamber, as set forth.

In testimony whereof I hereunto affix my signature in the presence of two witnesses.
